CLAIM

The ornamental design for a stainless steel sauce and soufflé cup holder, as shown and described.

DESCRIPTION

FIG. 1 is a front elevation view of a first embodiment of the stainless steel sauce and soufflé cup holder showing my new invention;

FIG. 2 is a rear elevation view thereof;

FIG. 3 is a side elevation view thereof;

FIG. 4 is a top plan view thereof;

FIG. 5 is a bottom plan view thereof;

FIG. 6 is a perspective view thereof;

FIG. 7 is a partial front elevation view with unclaimed environmental elements in the form of a cup;

FIG. 8 is a front elevation view of a second embodiment of the stainless steel sauce and soufflé cup holder showing my new invention;

FIG. 9 is a rear elevation view thereof;

FIG. 10 is a side elevation view thereof;

FIG. 11 is a top plan view thereof;

FIG. 12 is a bottom plan view thereof; and,

FIG. 13 is a perspective view thereof.

The broken line showing of parts of the drawings is included for the purpose of illustrating use and environment and forms no part of the claimed design.

1 Claim, 6 Drawing Sheets
